UNITED STATES PATENT OFFICE

114,046

DESIGN FOR TEXTILE FABRIC

Jules C. Shapiro, Pelham Manor, N. Y.

Application November 17, 1938, Serial No. 81,161

Term of patent 3½ years

To all whom it may concern:

Be it known that I, Jules C. Shapiro, a citizen of the United States, residing in Pelham Manor, county of Westchester, and State of New York, have invented a new, original, and ornamental Design for Textile Fabric, of which the following is a specification, reference being had to the accompanying drawing, forming part thereof.

The figure of the drawing is a plan view of the textile fabric showing my design.

I claim:

The ornamental design for textile fabric, as shown.

JULES C. SHAPIRO.
